INVENTOR

BY Marcus S. Lese

ATTORNEY

UNITED STATES PATENT OFFICE.

JOHN J. NOLTE, OF SAN FRANCISCO, CALIFORNIA.

REVOLVING PAN RACK.

Application filed September 7, 1921. Serial No. 499,041.

To all whom it may concern:

Be it known that I, JOHN J. NOLTE, a citizen of the United States, residing at San Francisco, in the county of San Francisco and State of California, have invented new and useful Improvements in Revolving Pan Racks, of which the following is a specification.

My invention relates to improvements in racks to be used in bakeries for holding the baking pans before they are placed in the oven or after they are removed therefrom, and it has for its object to provide a device of this nature capable of holding a maximum number of baking pans while occupying a minimum of space.

Another object of my invention is to provide means whereby the operator may readily load and unload the rack with the least motion on his part, thus saving time and labor.

With these objects in view I provide my device with a central upright stem secured to a portable base and upon said stem I mount the tubular center of the rack so as to turn freely.

A plurality of arms each forming two oppositely disposed pan shelves are secured to the tubular center one above the other in such a manner as to form four distinct vertical rows of shelves, thus bringing up the capacity of the rack to a maximum.

The rack body being adapted to turn around the central upright stem enables the operator to load or unload the entire contents of the rack without leaving his position by simply turning the rack and thus bringing closer one row of shelves after another as the work progresses.

The details of construction and the manner of operation of my device are illustrated in the accompanying drawings forming part of this specification.

Fig. 1 of the drawings is a perspective view of my device.

Fig. 2 is a vertical section through the center of the same.

Fig. 3 is a sectional plan of the device taken on line 3—3 of Fig. 2; and Fig. 4 is a side elevation of the lower portion of the device.

The device as shown consists of the circular base 1 furnished with the central hub 2 which is provided with a threaded bore 55 carrying the central upright stem 3.

Upon said upright stem 3 is mounted the tubular rack center which is formed of two light pieces of channel iron 4 placed with the flanges facing inwards and furnished at the top with a cast iron cap 5 formed with the seat 7 fitting the top of the stem and at the bottom with the lower cap 6 provided with the bore 8 fitting around the bottom of said stem.

A plurality of arms 9, 10, 11 and 12 secured to the tubular rack center are placed at regular intervals one above the other.

The said arms are made of light iron bars of rectangular cross section, bent in the form of two square frames diagonally disposed towards each other and joined together by the contracted portion 13 whereby they are secured to the tubular rack center 4 in the manner shown in the drawings, being placed with their center lines 75 alternately one at right angle to the other; the two square frames of each of the alternate arms are thus arranged in four vertical rows 9, 10, 11 and 12, each of said frames supporting a baking pan 14, as 80 shown in Figs. 3 and 4.

The circular base 1 is provided with the casters 15 in order to make the device portable. The device may be thus brought to the place where the baking pans are filled, 85 the several vertical rows of the shelves are there loaded in succession, keeping all the time the particular row of shelves which is being loaded in proximity to the location of the baking pans; the rack may be then 90 transported to the oven where one row of baking pans after the other are removed from the shelves and placed in the oven.

In due time the rack may be used for unloading the oven by placing the pans of the 95 baked product upon the shelves and then transporting the rack to the desired place to unload the contents.

Having thus described my invention, what I claim as new and desire to secure by Letters Patent is:

1. A device of the character described comprising an upright stem, an upright rack frame rotatively mounted upon said stem, and a plurality of shelves secured at a plurality of levels to said rack frame, the shelves at each level being separated by empty spaces and arranged to come vertically opposite the empty spaces between the shelves at the two adjacent levels.

2. A device of the character described comprising a portable base, an upright stem secured to said base, an upright rack frame rotatively mounted upon said stem, and a plurality of shelves secured at a plurality of elevations to said rack frame, the shelves at each level being separated by empty spaces and arranged to come vertically opposite the empty spaces between the shelves at the two adjacent levels.
3. A device of the character described comprising an upright rack frame, and a plurality of double shelves secured to said rack frame one above the other, each of
4. In a device of the character described an upright rack frame and a plurality of shelves secured at a plurality of levels to said rack frame, the shelves at each level being separated by empty spaces and arranged to come vertically opposite the empty spaces between the shelves at the two adjacent levels.

JOHN J. NOLTE
